CLAIM

The ornamental design for a large brew basket, as shown and described.

DESCRIPTION

FIG. 1 is a top left front perspective view of a large brew basket showing our new design;
 FIG. 2 is a front elevational view thereof; and
 FIG. 3 is a rear elevational view thereof;
 FIG. 4 is a left side elevational view, the opposite side being a mirror image thereof;
 FIG. 5 is a bottom view thereof;
 FIG. 6 is a top view thereof; and,
 FIG. 7 is a cross-sectional view thereof taken along line 7—7 in FIG. 6.
